(57) **CLAIM**

The ornamental design for a gaming controller, as shown and described.

DESCRIPTION

FIG. 1 is a top right side perspective view of a gaming controller;

FIG. 2 is a top left side perspective view thereof;

FIG. 3 is a back left side perspective view thereof;

FIG. 4 is a top back right side perspective view thereof;

FIG. 5 is a bottom left side perspective view thereof;

FIG. 6 is a bottom right side perspective view thereof;

FIG. 7 is a front view thereof;

FIG. 8 is a right side perspective view thereof;

FIG. 9 is a back side perspective view thereof;

FIG. 10 is a left side perspective view thereof;

FIG. 11 is a top view thereof; and,

FIG. 12 is a bottom view thereof.

The broken lines shown in the figures are for illustrating portions that form no part of the claimed design.

1 Claim, 12 Drawing Sheets
